UNITED STATES PATENT OFFICE.

ASA W. FARNEY, OF CLAY COUNTY, MISSOURI.

DIKE OR REVETMENT.

Application filed May 2, 1927. Serial No. 188,194.

This invention relates to dikes or revetments of that class employed in the protection of the banks of rivers and for reclamation work and for effecting changes in the course or channel of such streams, and more particularly the invention is designed as an improvement over that embodied in my pending application for patent on dikes, filed January 31, 1927, Serial No. 164,822.

It has occasionally happened after a mat or mattress has been formed, around piling, on the surface of a stream and before it has been feasible to securely anchor the screen poles to the mat, that the stream level has risen substantially above the mat and tie poles secured thereto, and has therefore made it difficult or impossible to nail the screen poles to the tie poles and hence anchor the former securely and dependably to the mat. Heretofore, under such conditions, the work would have to be abandoned temporarily at a considerable financial sacrifice or—sometimes at undue expense, a makeshift repair—effected which could safely be depended upon to retain its position.

My object is to provide a method of and means for effecting a strong and dependable connection of the screen poles to the mat even should the latter be submerged a foot or two, more or less, under water, and a further object is to accomplish this result quickly and inexpensively.

With the end in view mentioned, the invention consists in a method of and apparatus for securely and inexpensively connecting screen poles with a mat, as herein-after described and claimed, and in order that it may be fully understood reference is to be had to the accompanying drawing, in which:

Figure 1 is a fragmentary plan view of a dike or revetment constructed in accordance with the invention.

Figure 2 is an end view of the dike or revetment as it appears in Figure 1, showing the same as occupying its final or operative position with reference to the bed of a stream.

Figure 3 is an enlarged longitudinal section on the line III—III of Figure 1, and partly broken away, the parts appearing as operatively assembled prior to occupying their final or operative position with reference to the bed of the stream.

Referring now to the drawing in detail,

A, B and C respectively indicate the different rows of a series of piles 1, which are permanently driven into the bed of the stream to be equipped with a dike or revetment, and to form a part of such structure. 50 The row A indicates the row of piling on the upstream side, the row C, the row of piling on the downstream side, and the row B, the piling intermediate the rows A and C, it being understood of course that many 65 more of the rows of piling may be utilized according to the character of the work and other conditions which may suggest the advisability of a few or many rows of piling.

The rows of piling are braced longitudinally and laterally respectively by braces 2 and 3, bolted or otherwise securely fastened to the piling, the undermost row of braces, both the longitudinal and transverse braces, being secured as close to the water-line at 70 the time of the erection of the dike or revetment, as possible.

To stiffen the structure, it may be otherwise braced, as for example, by means of diagonal braces 4, which preferably extend 80 downwardly from the upper ends of the piles of row A to a point adjacent the water-line, to the piles of row C.

A mat 5 of the desired area, is now woven of twigs, branches, flexible poles and the like, or of any equivalent material, the construction being effected on the surface of the water and around the piling, the mat at opposite sides of the dike being woven on a barge and fed off the upstream end thereof as common in the art, while the portion of the mat between and adjacent the piles is woven by men working from temporary platforms (not shown), suitably supported by the lateral braces 3 or other parts of the 90 structure as found most convenient, as will be readily understood.

After the mat, or that portion of it corresponding substantially in area to the piling, is completed and resting on the surface 100 of the water, as explained, a series of longitudinal tie poles 6 are placed upon the mat and are tightly secured thereto adjacent the upstream side of the row of piles C, so that the force of the current tending to loosen 105 the tie poles will be resisted by abutment of the poles against said row of piles, it being also noted that the preferable mode of securing the tie poles in position, is by means of winding wire over the poles and through 110

the mat, as indicated at 7. It will be evident that when the tie poles 6 have been secured to the mat as set out, they effectively constitute a part of the body of the mat itself as they are permanently and securely fastened in place.

Assuming that after the work has progressed to the extent described, the water level rises from the water-line A, to the water-line B, for example, the weight and friction of the mat and tie poles on the piles will result in the submergence of the mat and tie poles to such an extent that it will be impossible to fasten the screen poles 8 by the method employed in my co-pending application above identified, that is, by nailing the screen poles to the tie poles, after the former have been forced down through the mat, as indicated in Figures 2 and 3.

It is necessary for proper anchorage of the screen poles against which filling material caused by erosion or otherwise will accumulate, to secure them firmly against working upward out of the mat and floating away. In the co-pending application as above stated, this is accomplished by nailing or otherwise securing the screen poles to the tie poles at or above the water level. In this case, assuming the tie poles to be submerged with the mat, the screen poles, after being thrust through the mat as above stated, are fastened together or in series by longitudinal bars 9 in a plane above the water level, the screen poles being nailed or otherwise securely fastened to the bars. The bars are then fastened securely to the tie poles by means of wires 10 looped around said bars and the tie poles, the workmen to accomplish this purpose, reaching under water and threading the wires between the mat and tie poles and then fastening the wires upon and above the bars twisting or otherwise fastening the ends of the wires together as at 11.

It will be evident that the screen poles when thus secured to the mat and tie poles, will project above the tops of the piling, as indicated in Figure 2, a distance substantially equal to the depth of the water below the mat, and in order to space the upper ends of the screen poles to hold them in proper relative position until the mat has settled to the bottom of the stream, as will hereinafter appear, a series of horizontal spacers 12 are nailed to each section of the screen construction between adjacent lateral rows of piling, it being understood that the connection between the screen poles and the spacers, is such as to allow for irregularities in the surface of the screen pole structure, upon the sinking of the mat, which is now gradually weighted by piling stone as at 13, or the like, upon the mat, the operation commencing at the upstream edge of the mat and progressing down stream as is

common in the art. The sinking of the mat will carry the screen poles down with it, and through the connection of the screen poles with the mat and with the longitudinal bars 9 and the spacers 12, the screen poles will be maintained in substantially the same relation as when originally secured in place before the lowering of the mat, it being understood that it is desirable to connect the upper portions of the screen poles, as if secured only near their lower ends, their upper ends under the force of the water, may bunch together and thus materially reduce the effectiveness of said poles as a screen.

As the mat finally settles upon the bed of the stream, the protruding and preferably sharpened lower ends of the screen poles will be embedded in the bed of the stream and thus cooperate to a degree in holding the screen poles in proper relationship. The upper ends of the screen poles under the pressure of the water, will abut against the upper rows of braces 2, and after the mat has permanently settled, the said ends of the poles are nailed or otherwise secured in position as shown at 14, in Figures 1 and 2.

It will be apparent that with the method of construction described in this application, it will be possible to properly anchor the screen poles to the mat even if the water level has risen to an extent to substantially submerge the mat and tie poles thereon, and it is to be understood that while I have described and claimed the method of construction which is preferable under conditions of rising water as mentioned, resort may be had to changes or modifications without departure from the spirit and scope of the appended claims.

What I claim is:

1. The method of producing a dike in a stream, comprising the sinking of upright piles to a sufficient depth in the bed of the stream for their proper anchorage, the formation of a mat upon the water and around and between the piles, the placing of a longitudinal series of upright screen poles in fixed relation to the mat, the connecting of a cross bar to the said screen poles at a point above the level of the stream, and the connecting of such bar to the mat by substantially upright wiring.

2. The method of producing a dike in a stream, comprising the sinking of upright piles to a sufficient depth in the bed of the stream for their secure anchorage, the formation of a mat around and between the piles on the surface of the stream, the securing of substantially horizontal tie poles upon the mat longitudinally thereof and adjacent the upstream side of the piles, the placing of a longitudinal series of upright screen poles in fixed relation to the mat and to the tie poles, the connecting of a cross bar to said screen poles at a point above the

level of the stream, and the connecting of said cross bar to the tie poles on the mat by flexible means.

3. The method of producing a dike in a stream, comprising the sinking of upright piles to a sufficient depth in the bed of the stream for their proper anchorage, the formation of a mat upon the water and around and between the piles, the placing of a longitudinal series of upright screen poles in fixed relation to the mat, the connecting of a cross bar to the said screen poles at a point above the level of the stream, the connecting of such bar to the mat by substantially upright wiring, and the connecting of the upright portions of the screen poles by stays.

4. The method of producing a dike in a stream, comprising the sinking of a plurality of rows of suitably spaced upright piles to a sufficient depth in the bed of the stream for their firm anchorage, the connecting of the piles by longitudinal and cross braces at different levels, the formation of a mat around the piles on the surface of the stream, the securing of longitudinally arranged and substantially horizontal tie poles on the mat against the upstream side of the downstream longitudinal series of piles, the placing of a longitudinal series of upright screen poles in fixed relation to the mat and

tie poles at the upstream side of the latter and the upstream side of the longitudinal braces for the downstream row of piles, the connecting of the screen poles by longitudinal bars at a point above the level of the stream, and the connecting by wiring of said bars with the said tie poles.

5. A dike comprising a plurality of rows of piles sunk into the bed of a stream a sufficient distance for firm anchorage, braces connecting the piles to form a substantially rigid skeleton framework, a weighted mat on the bottom of the stream through which the piles extend, tie poles securely fastened to said mat, a row of screen poles bearing against the upstream side of braces connecting the piles of the downstream row of piling and against the corresponding side of the tie poles and engaged at their lower ends with the mat, longitudinal bars connecting the screen poles, flexible connections between said bars and the underlying tie poles, spacers connecting the upper portions of the screen poles, and means securing the upper ends of said poles and said spacers in fixed relation to the piling structure.

In witness whereof I hereunto affix my signature.

ASA W. FARNEY.
